UNITED STATES PATENT OFFICE.

WILLIAM W. WALLACE, OF WILLOUGHBY, OHIO, ASSIGNOR TO J. W. PENFIELD & SON, OF SAME PLACE.

BRICK OR TILE CUT-OFF MACHINE.

SPECIFICATION forming part of Letters Patent No. 405,631, dated June 18, 1889.

Application filed September 27, 1888. Serial No. 286,501. (No model.)

To all whom it may concern:

Be it known that I, WILLIAM W. WALLACE, of Willoughby, in the county of Lake and State of Ohio, have invented certain new and useful Improvements in Cut-Off Mechanism for Tile or Brick Tables; and I do hereby declare the following to be a full, clear, and exact description of the invention, such as will enable others skilled in the art to which it pertains to make and use the same.

My invention relates to improvements in cut-off mechanism for tile or brick tables; and it consists in certain features of construction and in combination of parts, hereinafter described, and pointed out in the claims.

In the accompanying drawings, Figure 1 is a front end elevation. Fig. 2 is a side elevation. A A' represent metal side frames, the same being secured to metal cross-frames B B'. These cross-frames are open on what I will call the "back side," as shown in Fig. 1, so that by removing some of the lighter members of the machine and relaxing the endless apron F the latter intact can be removed from the table. The legs of the table consist of upright screw-threaded rods B' with feet b' attached. These screw rods or legs are held in sockets B² of the cross-frames, and the threads of the rods engage nuts b, the latter being in the form of hand-wheels, by manipulating which hand-wheels legs B' are elevated or depressed, as may be required—for instance, in adjusting the table vertically to correspond with the tile-machine, or in leveling the table on an uneven floor, or, if need be, to give an inclination to the table.

C and D are drums on which operate the endless apron F, these drums being mounted, respectively, on shafts C' and D'. Shaft D' is journaled in suitable stationary boxes connected with the side frame, while shaft C' is journaled in sliding boxes c, the latter operating in slots a of the side frame. To each box c is attached a screw-rod c', the latter extending through a hole in lug a' of the adjacent side frame, the rod outside the lug being provided with hand-nut c², by manipulating which latter the endless apron is tightened or relaxed, as may be required. Between the two drums the apron is supported by means

of a series of rollers f, the trunnions of these rollers being journaled in suitable boxes connected with the side frames.

O represents a bar of clay, one or more of which are forced out from the brick-machine 55 onto the endless apron F, and the clay adheres sufficiently to the apron to move the latter along with the bar of clay, and the apron in turn rotates the drums C and D.

Power is transmitted from drum D to mechanism that severs the bar or bars of clay into lengths for bricks or tiles, such mechanism being arranged as follows: Drum D is of such diameter that the drum is given just one revolution by means of the apron while the latter 60 is moving the length of a given number of tile or brick—in the present instance four—and consequently for every quarter-revolution of the drum D a brick or tile is severed. For severing the clay a wire i is provided, the wire 70 being stretched across the open side of yoke I. The one end of yoke is provided with a hook I', or some suitable device, for attaching the one end of the wire. The other end of the wire is connected with screw-rod i', provided 75 with thumb-nut i², the parts being arranged substantially as shown for tightening the wire. Yoke I reciprocates on vertical ways J by means of mechanism as follows: On shaft D' is mounted disk E and gear E', the latter 80 engaging pinion H' of shaft H, the diameters of gears E' and H' being as four to one. On shaft H are mounted two equal cranks h, set in line and connected by means of pitmen h' with trunnions I² of the yoke. With such arrangement of parts while the bar of clay is traveling the length of one brick or tile the yoke makes a stroke down and back, thereby severing the bar of clay, and the yoke returning to the place of beginning. For moving 85 the yoke along in unison with the bar of clay while the wire is making its cut, in order that the cut may be at right angles with the bar of clay, I provide as follows: The vertical ways J are rigidly attached to horizontal rods J', 90 the latter extending horizontally lengthwise of the table and reciprocating through guide-boxes a³ and a⁴, these boxes being connected with the side frames aforesaid. To the rear end of sliding rod J' are pivotally connected 100

at j' the hook-dogs K. Disk E and gear E' have each four laterally-projecting pins e, arranged in quadrant and concentric order, opposing pins being set in line with each other. 5 These pins are set at such radial distance from the axis of the shaft that they move in unison with the endless apron, and consequently move at the same speed as the bar of clay. The parts are so timed that just as the 10 wire i from above approaches the bar of clay hooks k of dog K engage the passing pins e, by means of which engagement the wire and yoke are moved along in unison with the bar of clay. Meanwhile the yoke and wire move 15 downward in making the cut, and are moved upward on their return-stroke while the wire is backing out of its own kerf, and just as the wire has passed above the bar of clay pins e draw off of, that is, become disengaged from, 20 hooks k, whereupon the recoil of springs j instantly returns the cutting apparatus rearward to the place of beginning, such rearward movement being limited by collar j^2 , adjusted on rod J', the collar engaging box a². Connected with boxes a⁴ are laterally-projecting pins a³, that limit the downward swinging movement of dogs K, and consequently support the dog during and after the disengagement of the dog from pins e. 25 3 Handles for moving the machine, these handles being pivoted to the side frames, as shown, so that when left free the handles by gravity turn down to a depending position.

Usually an endless belt (not shown) receives 35 the severed bricks or tiles.

In Fig. 1 three bars of clay are shown; but by changing the dies of the tile-machine a single and larger bar of clay might be substi-

tuted for the three smaller bars, if so preferred. The number and size of the bars of 40 clay will depend on the size of the brick-machine and the discharging-dies thereof.

What I claim is—

1. In a brick or tile cutting machine, the combination, with horizontally-moving carrier, of cutter reciprocating on vertical ways, such ways being mounted on horizontally-sliding bars, mechanism, substantially as indicated, for automatically actuating the cutter by the movement of the said carrier, substantially as set forth. 45

2. The combination, with horizontally-moving carrier, of cutter reciprocating on vertical ways, said ways being mounted on sliding bars, the latter operating in a plane parallel 55 to the movement of the carrier, mechanism, substantially as indicated, for operating the cutter and intermittently moving the cutter in unison with the carrier, substantially as set forth.

3. The combination, with endless apron and drums for supporting the same, of supporting-frame on which the journal-boxes of the said drums are supported, the said frames being open on the one side, substantially as indicated, whereby the endless apron may be removed from the table intact, substantially as 65 set forth.

In testimony whereof I sign this specification, in the presence of two witnesses, this 11th 70 day of May, 1888.

WILLIAM W. WALLACE.
